UTAKICHI KAWASAKI, OF SAN FRANCISCO, CALIFORNIA.

COVER-REMOVING DEVICE.

1,409,728.

Specification of Letters Patent. Patented Mar. 14, 1922.

Application filed June 21, 1920. Serial No. 390,373.

To all whom it may concern:

Be it known that I, UTAKICHI KAWASAKI, a citizen of the United States, residing at San Francisco, in the county of San Francisco and State of California, have invented new and useful Improvements in Cover-Removing Devices, of which the following is a specification.

This invention relates to improvements in cover or lid lifting devices of the type carried on the cover of a can or other receptacle and which operates when turned to lift the cover by pressing upon the receptacle.

The primary object of the invention is to provide a device of the character described which will be exceptionally cheap, simple, as to construction, reliable in operation, and which will do away with the necessity of punching a hole in the cover and the employment of a pivot pin whereby the air-tight seal of the cover is not effected.

It is possible with the cover lifting means of the art to rotate them through 360° and very often much difficulty is experienced in putting the cover back in place when these devices are turned in the wrong direction and lie in the way of the cover. Also, these devices work loose on their pivots after continued use and fail to operate properly.

My invention contemplates removal of the foregoing objections by provision of a device which cannot be turned completely around, and by elimination of pivot pins.

The invention possesses other advantages and features, some of which, with the foregoing will be set forth at length in the following description wherein I shall outline in full that form of the invention which I have selected for illustration in the drawings accompanying and forming a part of the present specification. In said drawings I have shown one form of the construction of my invention, but it is to be understood that I do not limit myself to such form, since the invention as expressed in the claims may be embodied in a plurality of forms.

Figure 1 is a fragmentary front elevation of a receptacle showing my invention applied thereto and in front elevation.

Figure 2 is a fragmentary side elevation of a receptacle partly in section, showing my invention thereon and a vertical section.

Figure 3 is a fragmentary top plan view of a detail of the invention.

Figure 4 is a top plan view of the movable

part of the device which works in the part shown in Figure 3.

Figure 5 is a front elevation of a modified form of the invention, showing it applied to a receptacle.

Figure 6 is a vertical sectional view of the device of Figure 5, showing it as applied to a receptacle.

Figure 7 is a fragmentary top plan view of a detail of the modified form shown in Figures 5 and 6.

Figure 8 is a top plan view of the other part of the device of Figures 5 and 6.

Figure 9 is a front elevation of another modified form of the invention shown as applied to a receptacle.

Figure 10 is a vertical section of the device of Figure 9 shown applied to a receptacle.

Figure 11 is a detail plan of a part of the device of Figures 9 and 10.

Figure 12 is a detail plan of the other part of the device of Figures 9 and 10.

Figure 13 is a top plan view of the lifting member as when formed.

Figure 14 is a side elevation of the member of Figure 13.

Figure 15 is a detail bottom plan of the part of the device on which the member of Figures 13 and 14 is mounted.

In the present embodiment of the invention, I employ a stationary member 16 on the lid 17 of a receptacle 18 and a movable or rocking member 19 associated with the member 16. The member 19 is adapted to engage the lid flange 20 on the receptacle when turning so as to effect a prying or lifting up action and to lift the lid from the receptacle.

In carrying out the invention, the lid 17 is provided with an extension 21 on one side thereof, of which extension the member 16 is formed, said lip being bent upwardly so as to parallel and lie spaced from the side of the lid, and being provided with an angular central opening 22. A tongue 23 extends from the lid at right angles thereto before the device is assembled. The opening is enlarged or under-cut, as at 24, at opposite sides so as to provide flanges 25 on opposite sides of the opening.

The member 19 is formed from a flat metal blank shown in Figure 4 and is bent right angularly as shown in Figures 13 and 14 so as to provide an operating or hand

portion 26. The other portion 27 of this member is cut so as to provide spaced legs 28 having cam edges 29. A tongue 30 extends from the portion 26 between the legs 28. The outside edges of the legs at their inner ends are notched as at 31. To assemble the device, the member 19 with its legs directed downward and its upper side below the member 16 is moved upwardly so that the flanges 25 extend into and through the notches 31. This causes the legs to extend behind the flanges and in this position the member 14 is moved upwardly until the portion 26 thereof reaches the upper side of the opening 22. The member 19 is prevented from movement laterally by engagement of the flanges 25 in the ends of the notches 31. The tongue 23 is then bent upwardly until it extends over and engages the tongue 30 and these tongues hold the parts in place. By turning the member 19 in either direction, it is rocked and one of the legs is moved downwardly behind one of the flanges 25 and presses upon the flange 20 on the receptacle. This forces the lid up and off of the receptacle. As the legs move down they extend through the enlargements 24 of said opening 22 in the member 16 and at all times are behind the flanges 25 so as to prevent outward withdrawal of the member 19.

It will thus be seen that with my device the lid may be quickly lifted by a slight turn of the member 19 and that said member is prevented from being turned through 360° it being permitted but approximately 45° of an arc in either direction. This insures the member 19 being in the right position when the lid is to be replaced. When this is done, the lid in engaging the projected leg of the member 19 will move said leg and member to normal position and this does not interfere with the replacing of the lid.

45 My device eliminates the forming of holes in the receptacle or cover proper and can be cheaply stamped out of sheet metal, quickly assembled, and when assembled, will not loosen but operate reliably at all times.

50 Referring particularly to Figures 5, 6, 7 and 8 the modified form shown therein comprises stationary members 33 formed on the cover 34 of a receptacle 35. This member 33 is tapered to a rounded point 55 towards its free end and is notched as at 36, on opposed sides thereof when joined to the cover, being bent up parallel to and spaced from the side of the cover. Near its free end, said member is provided with 60 an opening 37 formed by striking the metal inwardly. This provides a series of bandable tongues 38 around the edges of the opening. The member 39 is bent right angularly from a metal blank and one portion 65 thereof is notched or cut away at spaced

points as at 40 to provide legs 41 and a tongue 42 between and spaced from said legs. The tongue is formed with an opening 43.

In assembling this form of the invention, 70 the member 39 is placed with its legs 41 behind the member 33 and so that the handle portion 44 thereof extends outwardly over the upper edge of said member 33. The legs 41 extend through the notches 36 and are 75 rounded on their lower ends so as to engage and effect a prying up action on the flange 45 of said receptacle. The pivot for the member 39 is provided by extending the tongues 38 through the opening 43 and 80 bending said tongues outwardly. This secures the member 39 in place and provides an effective pivot. This form of the invention can also be moved in either direction to effect a lifting of the cover and cannot 85 rotate through 160° being limited as to this by engagement of the portion 41 with the member 33.

Referring to Figures 9, 10, 11, and 12, 90 the other modified form comprises a stationary member 47 bent up from and formed integral with the cover 48 in the same manner as the corresponding member of the other forms of the invention.

This member is provided with an angular 95 opening 49 therein and with two small slots 50 adjacent to the point where said member is joined to the cover. The right angular member 51 has two legs 52 having inward notches 53 therein at their inner ends. The opening 49 is formed with two slots 54 on opposite side of its outer end, said member being bent up to lie parallel and spaced from the cover. The material of the member 47 is bent out along the lower edges of 100 the slots 54 and the legs 52 are inserted through these slots and behind the member 47. The material is then bent back into 105 normal position and the member 51 is locked in place. By turning said member 110 51, one of the legs is extended through one of the slots 50 and will engage the cover flange 55 on the receptacle so as to lift the lid. This form is very simple and capable of being easily made and inserted.

115 I claim:

1. A receptacle cover remover comprising a receptacle, a cover for the receptacle, a member fixed to and bent upwardly on one side thereof and having an opening therein, 120 a rocking member having legs normally disposed between the cover and said fixed member and arranged to have said legs project through the opening and engage the receptacle when said rocking member is rocked, 125 a tongue on the cover extending into said fixed member and a tongue on the rocking member between the legs engaging behind and with the first named tongue.

2. A receptacle cover remover comprising 130

a receptacle, a cover for the receptacle, a member fixed to the cover and having an opening therein and a rocking member having legs disposed between the cover and said fixed member and arranged to have said legs project through the opening and engage the receptacle when said rocking member is rocked, a tongue on said fixed member bent to engage a part of the rocking member between the fixed member and the cover, and a handle portion on the rocking member extending outwardly therefrom through said opening.

5 10 15

3. A receptacle cover remover comprising a receptacle, a cover for the receptacle, a member integral with the cover and bent upwardly to lie substantially parallel to and spaced from, the side of the cover, said member having an opening therein, a rocking member having legs disposed between the cover and said integral member so that when rocked, the legs project through the openings and engage the cover, a tongue depending from the rocking member between the legs, and a locking tongue on the lid extending into the opening so as to be spaced from the sides and top thereof and engaging the outer side of the first named tongue.
